MESNE ASSIGNMENTS, TO CHARLES BATE, OF BOSTON, MASSACHUSETTS.

TELEPHONE-METER.

No. 851,090.

Specification of Letters Patent.

Patented April 23, 1907.

Application filed June 8, 1903. Serial No. 160,608.

To all whom it may concern:

Be it known that I, NEWMAN H. HOLLAND, of Brookline, county of Norfolk, and State of Massachusetts, have invented an Improvement in Telephone-Meters, of which the following description, in connection with the accompanying drawings, is a specification, like letters on the drawings representing like parts.

- 10 The present invention relates to a telephone meter of the kind located at the subscriber's station, the invention being shown as applied to a telephone meter system in which the operation of the meter depends upon the removal of the receivers at two connected subscriber's stations, the meter at the calling subscriber's station only being set in condition to operate when the calling subscriber removes his receiver to signal central, the
- 15 20 operation of the meter, however, not taking place until the called subscriber's line has been connected by the operator at central and said subscriber has taken his receiver from the hook.
- 25 It is the purpose of the present invention not only to simplify the meter controlling device, but also to provide means for preventing the recording of connections not satisfactory to the calling subscriber, in order that said subscriber need not be charged with a call which he has not used. It may happen for example that a subscriber may make a mistake in the number which he has called, for, or that the central office may 30 through error or misunderstanding connect the calling subscriber with the wrong line, in either of which cases it is not the purpose of the company to charge up the call. Again, it sometimes happens that the operator at 35 central office accidentally or inadvertently disconnects two subscribers before they have finished their conversation, thus necessitating another call which should not be charged. In accordance with the invention, the removal of the plug at the central office from the socket of the calling subscriber's line while said calling subscriber's receiver is off the hook, will cause the call which has been registered to be canceled through the
- 40 45 50 movement of the registering mechanism in its reverse direction, this happening, of course, in either of the cases above mentioned. For these purposes the actuating member which operates the registering

wheel is caused to remain in connection with 55 said wheel during the use of the telephone and to become disengaged from said wheel in response to the hanging up of the receiver while the line is still connected, as always happens during the regular use of the telephone. If, however, the line is disconnected by pulling out the plug at the central office while the receiver is down, the actuating device is returned to its normal position before it is disengaged from the registering 60 wheel, thereby restoring said registering wheel to the position from which it started, and canceling the call which was registered. The same cancellation will take place if the operator at central pulls out the plug before 70 the subscribers are through talking.

In a system to which the invention is applicable the meter actuating member, which is in the nature of a pawl, is controlled by a polarized armature under the influence of an electro-magnet in the normal telephone circuit, the terminals of which are permanently connected with a battery at central, there being however, a condenser in the bell circuit which prevents the current from flowing until the receiver is taken down. Upon taking down the receiver, therefore, and permitting the current to flow the armature moves in such a way as to cause the pawl to travel a certain distance and to engage a tooth of the registering wheel, which, however, is not moved during such movement of the pawl. At the central office there is a pole changing switch arranged to be controlled by the successive taking down of two receivers at connected stations, so that as soon as the stations have been connected and both receivers removed the direction of the current will be changed, causing a movement in the opposite direction of the polarized armature which moves 85 the recording wheel far enough to record a call. 90 95

In the construction which embodies the main feature of the present invention the pawl in its engaging and disengaging movement is controlled by a secondary member, the normal position of which is such as to hold the pawl out of the path of the wheel, the said secondary member being operated by the same current which operates the main armature, but being slower in its movement, so that the pawl will not come into engagement with the wheel until it reaches the 100 105

right tooth. The secondary member then remains in its abnormal position so long as there is current on the line, its armature being non-polarized, and the actuating pawl thus remains in engagement with the teeth after registration has taken place owing to its return movement. Under normal conditions the hanging up of the receiver and the disconnecting of the line at central office causes the magnet which operates upon the secondary armature to be deenergized so that the said armature returns to its normal position, removing the pawl from the wheel. If, however, the operator at central pulls out the plug while the receiver is still off the hook, the current of the original polarity will then be on the line, the polarized armature immediately moving back to its normal position and canceling the call before the slower moving secondary armature has caused the removal of the pawl from the wheel.

Figure 1 is a general diagram showing the circuits at the central office and two connected stations, the parts being shown in the position assumed when one of the two subscribers has taken down his receiver to call central prior to connection with the station desired; Fig. 2 is a view on an enlarged scale of the mechanical parts of the meter at one station; Fig. 3 is a similar view with part omitted showing the mechanism in a different position; Fig. 4 is a vertical section on line x^4 of Fig. 3 looking toward the left; and Fig. 5 is a view similar to Fig. 2, but showing a modification.

Upon removing the receiver at station 21 shown at the right hand side of the sheet the current from the main battery A will be caused to flow over the line wires owing to the short circuiting of the condenser B at station 21, thereby attracting the armature C and lighting the signal light D to notify central that connection is wanted. When central inserts the answering plug in order to communicate with the calling subscriber, a circuit is established through one of the electro-magnets E so as to attract one of the latch hooks F and remove the same from the engaging portion of the pole changing switch member G. The current which flows over the line upon removal of the receiver also passes through a shunt circuit in multiple with the transmitter comprising the conductors 1, 2, 3 and 4, including the electromagnetic coil a which energizes a core a^2 interposed between pole pieces b and b^2 of a permanent magnet b^3 . The polarity of said permanent magnet is such that a flow of current in the normal direction due to the taking down of the receiver will cause the core a^2 to be attracted by the pole piece b^2 , so that the said magnet is moved from its normal position shown at the left hand side of Fig. 1. This, as will hereinafter be described, sets the meter at the calling station in condition

to be operated in response to a movement of the core a^2 in the opposite direction, which movement takes place in response to the removal of the receiver at the remote station 210 when the receiver at said remote station is taken from the hook, after the stations have been connected.

The removal of the receiver at station 210 energizes the other of the electro-magnets E, thus causing the attraction of the other hook F, and the pole changing switch member G is then free to move toward the core of the electro-magnet H which is energized by current flowing through the connected circuits, thus causing a change in polarity of the current. This change in polarity immediately produces a movement of the magnet core a^2 toward the pole piece b which results in the movement of the train of wheels which operate the meter.

In accordance with the present invention the pole piece a^2 which constitutes the main actuating member of the meter mechanism is arranged to act upon a pawl c which actuates a counting mechanism such as a train of wheels of any suitable or usual type, not herein shown, by engagement with the main actuating wheel d of said train, which is shown as provided with a series of notches d^2 to receive the pawl c, (Figs. 2, 3, 4 and 5.)

The registration of a call depends upon a movement of the wheel d toward the left from the position shown in Fig. 5, and the original movement of the core a^2 previously described to the position shown in Fig. 5 causes the pawl c to enter one of the notches d^2 , as shown in said figure. Assuming, therefore, that the said pawl remains in the said notch during a movement of the core a^2 , in the opposite direction, to the position shown in Fig. 3, the wheel d will be turned the distance between two notches, thereby moving the counting mechanism in such a way as to register the call. This occurs, as has been previously stated, upon the removal of the receiver at the called subscriber's station.

In accordance with the present invention, however, the pawl c is not disconnected from the notch d^2 until conversation has been finished, and the receiver hung up, so that it is possible by producing a movement of the core a^2 from its normal position, which it assumes when both receivers are down, back to the abnormal position shown in Fig. 5, without disengaging the pawl from the notch d^2 , to restore the counting mechanism to the position from which it started and to thereby cancel the call which has been recorded. To accomplish this the pawl is further controlled by a secondary member e, which is shown as a lever pivoted at e^2 and provided with an armature e^3 in the field of the core a^2 , the said armature, however, being non-polarized and arranged to have a slower or more sluggish movement than that of the core a^2 ,

which is under the influence of the polarized magnet b^2 .

In the normal position shown in Fig. 2 in which the armature e^3 is retracted, the member e , which has an inclined guide surface e^4 to coöperate with a pin e^5 upon the pawl c , is in such position that the said pawl will be lifted and held out of the path of the periphery of the wheel d , so as not to enter the notch d^2 into which it would fall if left to itself. The slower movement of the secondary member e , therefore, causes the said member e to remain in such position as to support the pawl during the first movement of the core a^2 , so that the pawl will not be permitted to come into engagement with the periphery of the wheel d until it has passed beyond the notch which normally stands directly below the pawl, and it will therefore drop into the next notch as shown in Fig. 5, the core a^2 then being at the end of its movement so that the pawl will merely engage the wheel d without producing any movement thereof. The change of polarity due to the taking down of the called subscriber's receiver will then produce a movement of the core in the opposite direction, so that the pawl moves the wheel and registers the call. While the telephone is in use, however, a portion of the current will continue to flow through the coil a , and the parts will remain in the position shown in Fig. 3 with the armature e^3 of the secondary member e attracted to the core a^2 and the said core attracted to the pole piece b . Under normal conditions, therefore, there will be no change in the conditions until after the receiver has been hung up, thus short circuiting the coil a and deenergizing the core a^2 which permits the armature e^3 to return to its normal position, as shown in Fig. 2, thereby lifting the pawl c out of the notch d^2 and leaving the wheel d in the position to which it was moved when connection was first made, with the call duly registered. Assuming, however, that either the subscriber or the operator at central has made a mistake in the connection and that a call has been registered owing to the movement of the core a^2 in response to the taking down of the receiver at the wrongly connected station, it is possible in accordance with the present invention for the operator at central office to rectify the error by pulling out the plug at the central office as soon as she is informed by either subscriber that the mistake has been made, it being necessary only that the plug should be removed before the calling subscriber has hung up his receiver. This becomes practical for the reason that, as previously described, the pawl c remains in the notch d^2 during the conversation, being removed under normal circumstances by the operation of the secondary armature e^3 . The same cancellation of the record will take place, of course, if the operator at central inadvertently disconnects the

subscribers before they are through talking, thereby necessitating a new call, which should not be charged to the subscriber.

The position of the parts after connection has been established and conversation is being carried on is shown in Fig. 3, from which it will be seen that a movement of the core a^2 from the position shown in Fig. 3 to that shown in Fig. 5 will result in the restoration of the wheel d to the position shown in Fig. 5, i. e. the position from which it started, thus canceling the call which has been recorded by the movement of the wheel from the position shown in Fig. 5 to that shown in Fig. 3. It will be seen, furthermore, that if the plug is removed by the operator at central office while the receiver is off the hook at station 21, the connections through the pole changing device at the office will be broken and the current conditions upon the line will become the same as they were when the subscriber first removed his receiver; that is to say, the current will be of opposite polarity, thereby at once restoring the core a^2 to its normal position, without, however, releasing the armature e^3 .

The release of the pawl from the wheel d depends upon the release of the armature e^3 , which does not take place until the receiver has been hung up, such release taking place regardless of the position of the pawl, since the secondary member e normally holds the pawl in the position shown in Fig. 2 where it is entirely out of engagement with the wheel d .

It is obviously necessary that the movement of the armature e^3 should be slower than that of the core a^2 , or, more strictly speaking, that the pawl c should move with sufficient rapidity to pass beyond the notch d^2 over which it normally stands before it comes into engagement with the periphery of the wheel d , and this may practically be accomplished by the construction shown, in which the core a^2 acts through a lever a^3 , with which it is connected at a^3 , said lever being pivoted at a^4 and connected at its opposite end with a link a^5 connected with an elbow lever a^6 which has a bearing on the axis of the wheel train, the pawl c being pivotally connected to the arm a^7 of the said elbow lever.

The movement of the core a^2 , which is rapid in any event, owing to the fact that it is acted upon by a polarized magnet, is thus multiplied, so that the pawl c will be moved a sufficient distance before the more sluggish armature e^3 has been attracted far enough to carry the member e^4 out of the path of the projection e^5 . In the restoring operation, however, it is essential to provide means for insuring the maintenance of the armature e^3 in its abnormal or attracted position when the plug is taken out to cancel the call, in view of the fact that in taking out

- the plug the current may be short circuited at the central office, thereby momentarily deenergizing the whole system which would result in the immediate retraction of the armature e^3 and the lifting of the pawl c out of engagement with the wheel d . As indicated in Fig. 2, this is accomplished by providing the member e with a latch or retaining device f , the normal position of which is shown in Fig. 2, the said latch being pivoted at f^2 and provided with an offset weight f^3 , or equivalent therefor, to yieldingly maintain the said latch in the position shown. When, therefore, the armature e^3 is attracted 10 the projection e^6 on the tail e^6 of the member e rides up the surface of the member f and into the notch f^4 , so that the armature e^3 is held in its attracted position whether the core a^3 is influenced by current or not.
- 20 In order to release the member e and permit the same to return to its normal position after the coils a have become deenergized when the telephone is out of use, the member f is provided with an armature f^5 arranged to be acted upon by an electro-magnet g , which is included in a shunt circuit represented by the conductors 5 and 6, the switch hook 7, and conductors 4, 3, 9, 10, 12, 13 and 14, (Fig. 1).
- 30 While the receiver is off its hook, as shown at station 21, the current is short circuited by the receiver hook, and does not energize the electro-magnet g , which is of sufficiently high resistance to prevent it from being energized when the current has a free path through the hook. Assuming, therefore, that the receiver is down, the member e will be supported by the latch f , as shown, (Fig. 3) and if when the plug is pulled out at central office a short circuit takes place so that there is momentarily no current flowing through the station, the member e^3 will not be influenced in any way, and will not prevent the cancellation of the call as desired.
- 40 As soon, however, as the receiver is hung up, the current, whether it be of the polarity normally on the line when the plug is out, or of the opposite polarity which is on the line when the plug is in, will flow through the shunt circuit energizing the electro-magnet g and attracting the armature f^5 so as to release the member e and permit the parts to return to normal position, lifting the pawl out of normal engagement with the wheel d .
- 50 In order to prevent leakage of current through the shunt circuit when the line is not in use, the said circuit is provided with an automatic switch h , which is controlled by the member e , the said switch being herein shown as a receptacle of conducting material, the conducting wall of which is connected with the conductor 10 while the conductor 12 extends into the interior of the receptacle through an insulating member h^2 . The said chamber is connected with the member e so
- as to be tipped from the horizontal position shown at station 210 to the inclined position shown at station 21 when the armature e^3 is attracted, there being a drop of conducting substance, preferably mercury, indicated by 70 the reference letter h^3 , contained in said receptacle which will fall down into contact with the terminal of the conductor 12 when the armature e^3 is attracted or in its attracted position, thereby closing the shunt circuit 75 hereinbefore traced, which circuit, however, is opened at once upon the release of the member e through the action of the latch f . It is not essential, however, that the member e should be positively maintained, since under no circumstances will there be more than a momentary cessation of current, and the same object can be accomplished by other expedients. For example, as shown in Fig. 5, the tail e^6 of the member e may be connected with a dash pot piston f^{10} of any suitable or usual construction, which will insure such a slow movement of the armature e^3 as to prevent it from moving far enough from its abnormal position during any possible 90 cessation of current to prevent the proper operation of the pawl c .
- 85 The wheel d and the recording train carried thereby are normally held stationary by means of a locking device i , which is shown 95 as a weighted pawl adapted normally to engage with one of the notches d^2 , as shown in Fig. 2, the said pawl, however, being acted upon by a projection e^7 from the member e which carries the said locking pawl out of engagement with the wheel d , as shown in Fig. 5, when the armature e^3 is attracted. Therefore, even if the member e starts to move in time to permit the pawl c to rub over the periphery of the wheel d before it reaches the 100 desired notch, there will be no tendency for the wheel to be frictionally moved by the pawl prior to the engagement thereof with the right notch, since the locking device does not wholly become disengaged until the armature e^3 has been fully brought to its attracted position. Furthermore, while the said armature is in its fully attracted position as shown in Fig. 5, the wheel d will be free to be moved in either direction in response to the movement of the pawl c in accordance with the conditions previously set forth.
- 105 In the drawings Figs. 2, 3, 4 and 5, the circuit connections have been mainly omitted, these connections being shown as made through binding posts I, J, and K, (Fig. 2) which correspond to those shown in the diagram, so that it is believed that the connections can be clearly understood. In Fig. 125 5 there is no binding post I, since the magnet g is dispensed with in the modification shown.
- 120 So far as relates to the meter belonging to the called subscriber, there will under normal 130

circumstances be no movement of the recording wheel for the reason that the normal position of the core a^2 is that shown in Fig. 2, the polarity of the current on the line when 5 the instruments are connected and in use being such as to maintain the said core piece in said position, so that nothing happens at the called subscriber's instrument except the attraction of the secondary member e , which 10 merely lets the pawl down into engagement with the wheel. It may sometimes happen, however, that a subscriber having called for the central office without being successful in obtaining the desired connection, (assuming 15 for example that the other line is busy) will hang up his receiver before the plug has been disconnected at the central office, the result being that the core piece a^2 will be left in the abnormal position shown in Fig. 5, the pawl, 20 however, being lifted out of the notch d^2 by the retraction of the armature e^3 . Under these conditions if the subscriber should be called up by the central office his meter would be operated and the call recorded if the 25 pawl c were to be in engagement with the wheel d during the movement of the armature from the position shown in Fig. 5 to that shown in Fig. 3. The relatively slow movement of the secondary member e , however, 30 controls this, since the said member does not operate quickly enough to let the pawl down until it has passed beyond the notch in which it is shown in Fig. 5, so that no movement of the wheel d takes place and no call is registered. 35 This construction obviates the necessity for providing the instrument with any special appliances controlled for example selectively by incoming and outgoing signals, so that the construction is simplified, al- 40 though all conditions and emergencies are provided for.

In accordance with the invention, the meter coils are included in a shunt circuit around the transmitter circuit, this being a feature 45 of importance, since the meter circuit in that way is wholly under the control of the receiver hook, and furthermore, since the meter magnet affords no impedance to the talking current. Furthermore, this arrangement 50 of circuits makes it very easy to install the meter at any existing telephone station without changing the circuits in any way, the meter circuit being merely added.

The operation of the device may be briefly 55 described as follows: When a subscriber takes down his receiver to call central office the core a^2 moves rapidly from the position shown in Fig. 2 to that shown in Fig. 5, carrying the pawl c over the periphery of the 60 wheel, the said pawl being supported by the member e during such movement or a part thereof, so that it does not come into active engagement with the wheel until it reaches the right notch, as shown in Fig. 5, by which

time the member e has been acted upon to release the pawl and allow it to rest in the desired notch. After connection has been made at central office with the desired station, and the receiver at such a station has been taken down, the current of opposite polarity 65 is thrown on the line, causing a movement of the core a^2 in the opposite direction, thus carrying the parts to the position shown in Fig. 3, and registering the call. Assuming that no mistake has been made and the connection 70 is satisfactory, conversation will be carried on until finished, when both subscribers will hang up their receivers, the operator at central office leaving the connecting plugs in place until she gets her supervisory signals 75 from both stations. The hanging up of the receiver at the calling station will merely cut out the current flowing through the coil a , so that the armature e^3 will be retracted, the core a^2 remaining in the position which it has 80 assumed after a call has been registered, for the reason that no change of polarity will take place at the central office until the electro-magnet H is deenergized, which does not 85 take place until after the plugs have been 90 pulled out. The pawl c , therefore, is simply lifted out of engagement with the wheel d , and the parts restored to the normal position, shown in Fig. 2, the wheel d , however, having been turned one notch to the left to register 95 the call. Assuming, on the contrary, that either a calling or called subscriber finds that the connection is wrong, and so notifies the operator at central, the operator will at once pull the plug out of the calling subscriber's socket, this taking place naturally 100 before the calling subscriber has hung up his receiver, the result being that the polarity of the current flowing through the calling station is again reversed, so that the core a^2 is 105 moved back to its normal position, this taking place prior to the deenergizing of the magnet coils a , so that the secondary controlling member is not released and the pawl is not removed from the wheel. The call is thus 110 canceled.

The system in which the invention is embodied, may be briefly described as that in which a meter is operated through a change in the direction of current flowing over the 115 line. The system is equipped with means for changing the direction of the current in response to the taking down of the receivers at both stations connected, so that no registration can take place unless both parties are at 120 their stations. The invention, however, is principally embodied in the novel construction and arrangement of the mechanism which operates directly upon the recording device, and is not limited so far as relates to 125 the specific construction and arrangement of the means for changing the direction of flow of the current.

I claim.

1. In a telephone meter, an actuating wheel for the registering train; an actuating device co-operating with said wheel; an operating member movable in response to changes in the character of the current on the line to operate said actuating device; and a secondary controlling member for said actuating device to control the engagement thereof with the actuating wheel, substantially as described.
2. In a telephone meter, the combination with the actuating wheel; of a pawl to cooperate with said wheel; an electro-magnet; an armature movable in response to changes in character of current flowing through said electro-magnet to actuate said pawl; and a secondary controlling armature, provided with retarding means, to control the engagement of the pawl with the wheel, said armature being non-polarized and attracted regardless of changes in the character of current on the line, as set forth.
3. The combination with the actuating wheel; of a pawl to cooperate with said wheel; a controlling member normally holding the said pawl out of engagement with said wheel; an operating member for said pawl adapted to move quickly in one direction or the other in accordance with the character of the current flowing through the instrument; an electro-magnet to receive such current; a non-polarized armature for said controlling member; and means for causing said armature to move more slowly than the said operating member, as set forth.
4. The combination with the actuating wheel; of a pawl cooperating therewith; a quick moving polarized armature to operate said pawl; a controlling member provided

with a relatively slow moving armature to control the engagement of said pawl with the actuating wheel; an electro-magnet to operate said armatures; and a locking device for said wheel operated by said slow moving armature, as set forth. 45

5. The combination with the actuating pawl and its operating member; of a controlling device for said pawl; a locking member for said controlling device; an electro-magnet cooperating with said locking member; a circuit for said electro-magnet; and an automatic switch in said circuit operated by said controlling device, as set forth. 50

6. In a telephone metering system, a meter or recording device at each station; means for operating said meter in response to the consecutive action of currents differing in character; means for causing a current of one character to flow through a station in response to the closure of the telephone circuit at said station prior to the insertion of a plug in the jack belonging to said station; means for thus closing the telephone circuit at said station; a device for changing the character of the current operating in response to the closure of the telephone circuits at two stations connected together at the central office; and means located at the station for restoring said meter in response to the re-changing of the character of the current which takes place when the plug is removed from the jack while the telephone circuit is closed. 60

In testimony whereof I have signed my name to this specification in the presence of two subscribing witnesses. 75
